UNITED STATES PATENT OFFICE.

EUGENE A. CROWE, OF NEW YORK, N. Y., ASSIGNOR TO THE E. S. HIGGINS CARPET COMPANY, OF SAME PLACE.

DESIGN FOR CARPET.

SPECIFICATION forming part of Design No. 30,511, dated April 4, 1899.

Application filed February 18, 1899. Serial No. 706,082. Term of patent 7 years.

To all whom it may concern:

Be it known that I, EUGENE A. CROWE, a citizen of the United States, residing at the city of New York, borough of Brooklyn, in the county of Kings and State of New York, have invented and produced a new and original Design for a Carpet, of which the following is a full specification, reference being had to the accompanying drawing, forming a part thereof, in which is represented a plan view of a portion of a strip of carpet embodying the features of my design.

The design consists in a carpet comprising the representation of a shield having emblazoned thereon an ax and a mallet, the handles whereof are crossed, and a wedge between the mallet and the ax-heads. Foliate sprays are arranged beneath the shield and floral sprays at the sides and top of the shield.

A horn of plenty appears in conjunction with the shield; also, a pair of scales and a vase, the vase apparently receiving a cup or platform of the scales. The space between the various figures is supplied with foliate and floral decorations. 25

The essential feature of the design consists in a carpet comprising the representation of a shield decorated with an ax, a mallet, and a wedge, associated with a horn of plenty and a pair of scales and a vase. 30

I claim—

The design for a carpet, herein shown and described.

EUGENE A. CROWE.
